UNITED STATES PATENT OFFICE

2,599,548

MACHINE FOR THE MANUFACTURE
OF SHOES

Walter F. Field, Brockton, Mass.

Application November 9, 1949, Serial No. 126,406

5 Claims. (Cl. 12—51)

1

This invention relates to the manufacture of shoes and more particularly to a machine for the direct, progressive adhesive application of welting to the bottom of a lasted shoe upper.

In the past, welting has been associated with shoe uppers in various ways. Thus in the so-called Goodyear welt shoe the welt is secured to the rib of a ribbed insole by stitching in a so-called inseaming operation and subsequently the outside is stitched to the welt. In another type of welted shoe such as illustrated in my Patent No. 2,345,738 the welt may first be attached to the margin of the outsole as by stitching, and the assembled welt and outsole subsequently secured to the upper as by means of adhesive.

In my co-pending application Serial No. 126,407 filed on even date herewith I have disclosed and claimed a shoe construction and method of preparing such shoe involving the application of a welt to the margin of a shoe bottom by means of a high strength pressure sensitive adhesive such as neoprene and the subsequent attachment of an outsole to the welt. The present invention is directed to a machine construction whereby a welt readily may be directly progressively and adhesively applied to a shoe bottom with a uniform marginal extension of the welt beyond the upper.

An object of the invention is to provide a machine whereby a welt readily and rapidly may be adhesively applied to the margin of a shoe bottom. A further object is to provide such a machine whereby the welt may be located with a predetermined extension beyond the shoe margin regardless of the particular shape of the shoe bottom.

Other objects will be apparent to those skilled in the art from the disclosures herein made and from the accompanying drawings wherein

Figure 1 is a top plan view of the machine showing a piece of welting in operative position;

Fig. 2 is a side elevation of the machine;

Fig. 3 is a front elevation of the machine;

Fig. 4 is a fragmentary vertical section showing a shoe upper in cooperative relation with welting and with the machine during the application of a welt to the shoe; and

Fig. 5 is a side elevation, partly in section, of a modified form of machine wherein positive driving means is provided for the edge gauge.

I have illustrated in the drawings a preferred form of machine arranged for the adhesive application of a welt to a shoe. Conveniently there may be employed welting which is patented per se in my Patent No. 2,345,738. The grain side

2

of this preferred welting, before attachment to the shoe, is flat, and the inner portion of the grain side is roughed for the more ready reception of adhesive. The flesh side of the welt is provided with a longitudinal channel and on the inner side of the welt the flesh side tapers toward the grain side. The outer portion of the welt is of substantially uniform thickness.

In the form of my machine which I have 10 herein illustrated in Figs. 1 to 4 inclusive there is provided (see Fig. 4) a positively driven pressure roll mounted on a horizontal axis and an edge gauge or guide which is shown as rotatable. The driven pressure roll is provided with a circular flange, or what might also be termed an elevated welt guide, which flange is arranged to cooperate with the longitudinal channel in the upper surface of the welt to guide the welt and to prevent lateral movement thereof. A recess 15 in the upper portion of the edge gauge serves additionally to inhibit lateral movement of the welt toward the center of the edge gauge during its application to the welt of the shoe. In the application of the welt to the shoe the inner portion 20 of the lower or grain side of the welt has previously been coated with suitable pressure sensitive adhesive and the marginal portion of the shoe bottom has likewise been coated with suitable pressure sensitive adhesive. For the welt applying operation the lasted upper is held manually, and is pressed laterally against the edge guide and upwardly against the welt and positively driven roll. The upward pressure against the positively driven roll serves to rotate the lasted upper for the marginal application of the welt thereto. Such upward pressure, furthermore, serves to cause the pressure sensitive adhesive coated surfaces to adhere initially. Subsequently the welt and lasted upper may be placed under sole attaching pressure to provide an adhesion between the welt and lasted upper sufficient to hold the parts together during the life of the shoe.

In Fig. 5 there is illustrated a modified form 45 of machine in which the pressure roll and the edge gauge are both driven positively and in synchronism.

Reference will now be made to the details of construction in the illustrative embodiment of my invention shown in Figs. 1 to 4 inclusive. Thus, there is mounted on the base 2 a motor 4 having a shaft 6. To the shaft 6 is keyed a worm 8 arranged in driving relation to a gear 10. Also mounted on the base 2 is the post 12 which carries the elements which cooperate with the welt-

ing and shoe upper. Journalled in the upper and elongated portion 14 of the post 12 is the shaft 16 which rotates in the bearing 18. At the forward end of the machine, the shaft 16 carries the positively driven pressure roll 20 which is shown as having an inner portion 22 of uniform diameter, a circumferential flange or elevated welt guide 24, an outwardly flaring portion 26, and an outer portion 28 of uniform section. The gear 10, previously mentioned, is keyed to the rearward end of the shaft 16 and additionally secured to the shaft 16 by the screw 13. When the motor is running, therefore, the pressure roll 20 is continuously rotated.

Slidably movable in the slot 30 is the gauge bracket 32 which is adjustable in a direction parallel to the shaft 16 and pressure roll 20. At its forward end, the adjustable bracket 32 is decreased in thickness but increased in width to form the forward section 34. This forward section 34 carries in freely rotatable fashion the rotary gauge 36, which is shown as mounted for rotation on a vertical stud 38 which is threaded at the screw portion 40 into the forward bracket section 34. A bushing 42 is shown as provided adjacent to the stud 38. The gauge 36 is thus rotatable in idler fashion.

The rotary gauge 36 is shown as provided with a cylindrical surface 44 which is arranged to engage the side surface of the shoe upper 46 directly adjacent to the margin 48 thereof. This cylindrical surface 44 may be made very narrow, in order that the place of contact between the rotary gauge and the shoe may be as close as possible to the bottom of the shoe. Directly below the cylindrical portion 44 the gauge 36 is shown as recessed or tapered inwardly to form a conical portion 50. The inwardly tapering section 50 makes it possible for the cylindrical section 44 of the gauge to contact with the side of the upper 46 directly adjacent to the margin 48 thereof regardless of the contour of the side of the upper at any portion thereof. The cylindrical section 44 of the gauge 36, therefore, need never be of vertical extent greater than necessary to make satisfactory contact with the side of the shoe upper 46.

The upper portion of the gauge 36 is recessed to provide a horizontal welt-supporting surface 52, and a vertical surface 54 which may be employed to cooperate with the outer surface or edge of the welt.

It will be observed in the construction illustrated (see Fig. 4) that the welt 56 is guided or held against any lateral movement, by the elevated welt guide or flange 24, and is further held against lateral movement outwardly of the shoe upper by the vertical surface 54 of the gauge 36, and that the welt is guided or held against vertical movement by the surfaces of the pressure roll 20 and by the horizontal surface 52 of the gauge 36. In this way the welt 56 is held in predetermined relation with respect to the shoe 46. To accommodate welting of other dimensions suitably dimensioned pressure rolls 20 and gauges 36 may be substituted. This may require lateral adjustment of the gauge 36 for which provision is made. Thus, downwardly from the forward portion 34 of the bracket 32 is the yoke 58 (see Fig. 2) and cooperating therewith is the yoked adjusting screw 60 which extends into the boss 62. The bracket 32 may be adjusted laterally by turning the adjusting screw 60. At the desired lateral position the bracket 32 may be fixed

in place by tightening the screws 64 which extend through the slots 66.

Means is provided for guiding the welt from a suitable source such as a reel (not shown) to the pressure roll 20 and rotary guide 36. Thus, a bracket 68 is provided, one arm 70 of which is secured to the upper portion of the post 12 by screws 72, and the other arm 74 of which is secured as by brazing to a welt tunnel 76.

The specific form of welting 56 illustrated in the drawings is shown as having a longitudinal channel 78 in its upper or flesh side, as being of uniform dimension outwardly of the channel 78, and as tapering downwardly from the flesh side toward the lower or grain side inwardly of the channel 78. The lower or grain side 80 of the welt 56 is preferably roughed on the inner portion thereof and coated with an active pressure-sensitive adhesive. The margin 82 of the upper likewise ordinarily is coated with active pressure-sensitive adhesive prior to the welt-applying operation.

In the ordinary use of the machine, it is convenient to rotate the pressure roll 20 at a rate in the neighborhood of about 100 revolutions per minute, but this rate may be increased as convenience may suggest.

In Fig. 5 there is shown a modification of the invention wherein the edge gauge and the pressure roll are both positively driven, and in synchronism. This machine differs from that shown in Figs. 1 to 4 particularly in the feature of construction of the pressure roll and edge gauge, and in the positive driving means therefor. Thus in Fig. 5, on the base 2 is mounted a motor 4. To the motor shaft 6 is keyed a worm 8, which drives the gear 10. The post 12 is also mounted on the base 2. Journalled in the upper and elongated portion 14 of the post 12 is the shaft 17 which rotates in the bearings 18. At the rearward end of the shaft 17, the gear 10 is keyed to the shaft 17 at 11 and additionally secured to the shaft by the screw 13. At its forward end, the shaft 17 carries a bevel gear 84 and a pressure roll 85. Both the gear 84 and the roll 85 are keyed to the shaft 17 at 86, and are additionally secured to the shaft by the screw 87.

The pressure roll 85 is generally similar to that shown in Figs. 1 to 4, and has an inner portion 88 of uniform diameter, a circumferential flange or elevated welt guide 89, an outwardly flaring portion 90, and an outer portion 92 of uniform diameter, which may function as an extension of the inner portion 88 of the pressure roll.

As in Figs. 1 to 4, the gauge bracket 32 in Fig. 5 is slidably movable in the slot 30 to provide adjustability of the bracket in a direction parallel to the shaft 17 and pressure roll 85. The bracket 32 has a forward section 34 of reduced thickness and increased width which carries the positively driven rotary gauge 51.

The gauge 51 is shown as mounted for rotation on a vertical stud 53 which is threaded at the screw portion 55 into the bracket section 34. A bushing 57 surrounds the stud 53. The gauge 51, as illustrated, has a downwardly tapered bottom section 59, rubber-like lamination 61, and a thin metal top lamination 63. The object of the rubber-like lamination 61 is to provide a cylindrical surface 65 suitable for contacting the side of a shoe upper in non-slip fashion. A bevel gear 67, shaped to mesh with bevel gear 84, is mounted on lamination 63, and the gauge sections and the gear 67 are held together by screws 69.

In the operation of the machine for the ap-

application of a welt to the marginal portion of the shoe bottom, the operator presents the lasted shoe upper to the machine (see Fig. 4) with that edge of the shoe which is adjacent to the shoe bottom in juxtaposed relation to the cylindrical surface 44 of the edge guide 36. The portion of the edge of the shoe first presented to the machine is ordinarily where one end of the welt is to be located, which is commonly opposite the breast line of the heel. When the operator is ready to start the application of the welt to the shoe, he presses the lasted shoe upper 46 upwardly against the pressure roll 20. This begins the feeding of the welt 56 and the rotation of the shoe. The operator holds the shoe in hand, turns it around the toe and brings it to the point where the welt is to end. At this point the operator releases his pressure against the pressure roll 21, and cuts off the welt. It will be understood that the feeding of the welt, and the application thereof to the shoe, takes place only so long as the operator presses the shoe upwardly against the pressure roll 20. As previously indicated, at the time the welt applying operation takes place the cooperative surfaces of the marginal portion of the shoe bottom and of the welt are coated with pressure sensitive adhesive in active condition, so that when the parts come into contact they adhere immediately.

Various modifications of the machine may of course be made while still coming within the scope of my invention. Thus it has been pointed out that the pressure roll 20 has an elevated welt guide or flange 24 which cooperates with a channel in the welt to prevent lateral movement of the welt. Broadly speaking the pressure roll 20 and the welt have cooperative surfaces which prevent lateral movement of the welt. It will be understood of course that these cooperative surfaces might comprise a groove in the pressure wheel 20 and an elevated strip in the welt. Generally speaking, the pressure roll 20 and the welt may have any suitable shape for their cooperating surfaces. Other mechanical expedients and equivalents will be obvious to those skilled in the art. Furthermore in certain cases the cooperative raised and depressed portions on the pressure roll 20 and welt might be omitted and guide member 36 relied upon to prevent lateral movement of the welt.

The guide 36 is shown as freely rotating in the specific embodiment illustrated herein, but in certain cases this guide may be stationary rather than rotary and the invention is intended to cover this expedient. Generally speaking, however, the rotary guide is preferred because of its lessened friction on the sides of the shoe.

It will be seen from the above that I have provided a machine of simple and sturdy construction by means of which a welt readily may be applied to the marginal portion of the bottom of a flat lasted or slip-lasted upper, and at a speed which is limited only by the capacity of the operator.

It will further be noted that the machine involves a substantial factor of safety in so far as the safety of the operator is concerned as well as the spoilage of material. This will be readily apparent when it is considered that the operator need merely release his pressure against the pressure roll 20 to stop the feeding of the welt and the movement of the shoe.

It should further be noted that while the pressure roll 20 has been shown with its axis in horizontal position and the rotary guide has been

shown as disposed vertically there beneath it will be understood that these parts may be arranged in any desired position so long as the relative position of these parts is maintained. But the axis of the pressure roll might be in a position other than horizontal and the rotary guide might be above the pressure roll rather than below or at any intermediate position.

It will of course be understood that my machine may be suitably disposed by fastening it to a stand of the usual type or to a table so as to bring the operative parts to the desired height with respect to the operator.

Various changes may of course be made in the machine without departing from the invention as defined.

Having described my invention, what I claim as new and desire to secure by Letters Patents of the United States is:

- 20 1. A machine for the application of welting to a shoe bottom comprising in combination a positively driven pressure roll rotating on a horizontal axis, a guide member rotatable on a vertical axis, said guide member being shaped at its upper portion to cooperate with said pressure roll to receive and support the outer portion of a welt, said pressure roll extending over the entire width of the welt, said pressure roll having a circular flange or elevated welt guide arranged to cooperate with a corresponding channel in the welt to prevent lateral movement of said welt and a welt tunnel to guide the welt to the cooperating pressure roll and rotary guide member.
- 25 2. A machine for the application of a welt to a shoe bottom comprising, in combination, a positively driven pressure roll rotatable on its own axis, said pressure roll being shaped to extend laterally over a welt and over the marginal portion of a lasted shoe bottom, said pressure roll being shaped peripherally to cooperate with a correspondingly shaped welt to preclude lateral movement of said welt, guiding means arranged to cooperate with the side of the shoe adjacent to the shoe bottom in a position close to but not in direct contact with said pressure roll whereby when the side of a lasted shoe is pressed against said pressure roll the welt is progressively applied to the marginal portion of the shoe bottom.
- 30 3. A machine for the application of a welt to a shoe bottom comprising, in combination, a driven pressure roll rotatable on its own axis, said roll being shaped to extend over and to cooperate with a welt and the marginal portion of a shoe bottom, guiding means rotatable on an axis perpendicular to that of the pressure roll, said guiding means being disposed closely to the pressure roll so as to support a welt adjacent to but not in contact with said pressure roll, said guiding means being shaped laterally to guide a shoe, said parts being so shaped that when the edge of a shoe adjacent to the shoe bottom is presented to said guiding means and pressure roll the lateral inner portion of the welt extends over the marginal portion of the shoe bottom for progressive application thereto.
- 35 4. A machine for the application of a welt to a shoe bottom comprising, in combination, a positively driven pressure roll rotatable on its own axis and arranged to cooperate with a welt over the entire lateral surface thereof; a guide member disposed in fixed relation to said pressure roll and shaped to support the outer lateral portion of a welt, to preclude outward movement of the welt, and to cooperate with the side of a lasted
- 40
- 45
- 50
- 55
- 60
- 65
- 70

shoe; said pressure roll projecting inwardly beyond the guide member to permit a lasted shoe bottom to be pressed against the inwardly projecting portion of the pressure roll and the interposed inner lateral portion of a welt.

5. A machine for the application of a welt to a shoe bottom comprising, in combination, a positively driven pressure roll rotatable on a horizontal axis and arranged to cooperate with a welt over the entire lateral surface thereof; a 10 guide member rotatable on a vertical axis in fixed relation to said pressure roll, said guide member being shaped to prevent outward lateral movement of said welt and having a vertical guide surface arranged to cooperate with the side of a lasted shoe; said pressure roll and guide member being cooperatively shaped to support loosely

therebetween the outer lateral portion of a welt, said pressure roll projecting inwardly beyond said vertical guide surface to permit a lasted shoe bottom to be pressed upwardly against the inwardly projecting portion of the pressure roll and the interposed inner lateral portion of a welt.
